UNITED STATES PATENT OFFICE.

DAVID H. DONEGAN, OF SAWPIT, COLORADO.

ORE-CONCENTRATOR.

1,352,882.

Specification of Letters Patent. Patented Sept. 14, 1920.

Application filed April 14, 1920. Serial No. 373,851.

To all whom it may concern:

Be it known that I, DAVID HUBERT DONEGAN, a citizen of the United States of America, residing in the town of Sawpit, county 5 of San Miguel, and State of Colorado, have invented certain new and useful Improvements in Ore-Concentrators, of which the following is a specification.

This invention relates to a concentrator 10 for the metal or metal compounds found in metal bearing ores or earth, and aims to provide improvements therein.

The invention provides a sluice or riffle-board of improved construction and opera- 15 tion.

The invention further provides a hydraulic gravity separator, preferably in combination with the sluice board, for effecting separation of metals or metal compounds 20 from the earth or gangue which the metals or metal compounds are associated with; or of concentrated portions of the ore, in the case where the hydraulic gravity separator is used in conjunction with the sluice, for 25 separating the concentrates coming from the sluice.

The invention further provides a sluice or riffle-board in which the riffles are automatically cleaned.

30 The invention further provides, preferably in combination with the sluice and hydraulic gravity separator, a screen by which a further separation of the metal or metal compounds may be effected.

35 The invention further provides a novel arrangement, and combination, and sub-combination of parts, together with novel elements, as hereinafter more fully set forth, and as defined in the annexed claims.

40 An embodiment of the invention is illustrated in the accompanying drawings:—

Figure 1 is a top plan view of the concentrator as a whole.

Fig. 2 is a vertical cross section on the line 45 II—II Fig. 3.

Fig. 3 is a longitudinal section on the line III—III Fig. 2.

In said drawings:—

Numeral 10 designates a sluice or riffle-board, which may be of any suitable construction but is preferably in the form of a board or sluice having riffles in the form of pockets 12 therein. The riffles or pockets may be of any desired shape and may be set 50 or formed at any desired angle across the riffle-board. These pockets 12 preferably ex-

tend below the surface of the bottom 11 of the sluice. The riffles or pockets 12 preferably extend directly across the board or sluice, and the walls of the pocket on the 60 side which is in the direction of flow of the sludge or slimes is preferably inclined in said direction of flow, as indicated by numeral 15. The opposite wall 17 of the pocket is also inclined, so that said wall is 65 undercut or overhangs the bottom of the pocket.

There is also preferably an outlet from the pocket, as for example the narrow slot 19. This slot preferably communicates with 70 a conduit 21 leading off to any suitable device or place for collecting the concentrates. The conduit 21 is preferably in two parts, leading off the water containing the concentrates to the two sides of the sluice. Of 75 course a conduit leading off to one side of the sluice only may be employed if desired. The outlet from the pocket provides for automatically cleaning the riffles.

The concentrates flowing off through the 80 conduit 21, preferably before being collected, pass through a hydraulic gravity separator 23 for effecting the further concentration of the metal values. The device 23 preferably comprises a pipe or conduit 24 85 having an upwardly directed portion with a spout 25 through which the water may flow. The lighter portions of the concentrated matter suspended in the water are carried upward with the water, and pass off 90 through the spout 25. The heavier portions sink to the bottom of the conduit 25. Preferably, however, the device 23 comprises a second conduit or spout 27 through which a portion of the water flowing into the con- 95duit 24 may flow and carry with it the concentrated metal values which are not carried upward by the stream through the spout 25, thus providing for a continuous separation of the lighter and heavier sus- 100pended particles, and the continuous carrying off of the heavier suspended particles through the spout 27.

The rate of flow through the spout or conduit 27 is preferably controlled by means 105 of a valve 28. By regulating the opening controlled by the valve 28 the separation of the lighter and heavier particles may be regulated. There may be a set of these hydraulic gravity separators on the two sides of the 110 sluice, where the sluice is made with the conduit 21 leading off to the two sides.

A gutter 31 may be provided for carrying off the liquid and light suspended matter or gangue flowing from the spout 25.

The concentrates passing through the conduit 21, or through the conduit 21 and the hydraulic gravity separator 23 may be collected in the bottom of a trough 35, which trough may also serve as a support for the sluice 10 and gutter or gutters 31.

10 Preferably, however, the water carrying the concentrates flows on to a screen 40. This screen is conveniently in the form of a perforated plate 41 having on top thereof a bed of finely divided inert material 43, as for example shot. The heavier material will work its way through the shot or other inert material to the bottom of the trough, while the gangue will be in large part caught and retained in the bed of the screen.

20 The concentrates in the bottom of the trough may be run off through vertical pipes 50 connected with a main pipe 52 leading off to a suitable place of collection or receptacle for holding the values.

25 A head gate 55 may also be placed at the end of the trough. The height of this head gate may be chosen by the user so as to give the best results. The water flowing over the head gate 55 will carry away with it any light particles suspended therein and passing through the screen 40.

The operation of the device is as follows:—

30 The sludge or slime, formed in any suitable manner, is conducted to the head of the sluice or riffle-board 10, and flows over the riffle-board in the direction indicated by the arrow. The stream will carry the lighter particles of dirt or gangue with it over the end 50 of this sluice. The heavier particles will drop to the bottom of the stream, and collect in the riffles or pockets 12. Where the pockets 12 are provided with an outlet, the concentrates which collect in the pockets 12 flow out, with a part of the water through 40 the conduits 21, thereby automatically cleaning the riffles. Where the conduits 21 are provided with hydraulic gravity separators, the stream containing the concentrates flows through these separators 23, the lighter particles being carried upward by the part of the stream which escapes through the spout 25 and is carried off through the trough 31. The part of the stream carrying the heavier particles of the concentrated material 45 flows off through the other spout 27, and preferably flows on to a screen, which screen effects a further separation of the heavier from the light particles, the heavier particles working through the screen. The concentrates or values passing through the screen are preferably carried off through the pipes 50, 50 to a collection receptacle. The water flowing over the head gate 55 will carry away with it any light particles flowing through 60 the screen. However, this head gate may

be adjusted so that all of the water flows off through the pipes 50, 52.

The action of the hydraulic gravity separator 23 is controlled by operating the valve 28. This controls the rate of flow through the spout 27, and consequently controls the rate of flow through the spout 25. The greater the flow through the spout 25, the greater will be the ability of the stream flowing through the spout 25 to carry with it portions of the suspended matter flowing into the separator 23. The regulation is effected so that the greatest amount of gangue escapes through the spout 25, and all or the greater portion of the metal values passes off through the spout 27.

The inventive ideas herein set forth may receive other embodiments than those herein specifically illustrated and described.

What is claimed is:

1. A concentrator for metal bearing ores or earths, comprising a sluice and a series of riffles in said sluice, said riffles being in the form of pockets below the bottom of said sluice, and an outlet from said pockets for carrying off the concentrates settling in said pockets during the running of the sluice, and means for effecting a further separation of the gangue in said concentrates from the metal therein, said means comprising an upwardly directed spout connected with said outlet through which the liquid carrying the lighter portions of the concentrates may flow, and a second spout through which the liquid carrying the highly concentrated metal may flow, and a screen into which said second named spout discharges.

2. A concentrator for metal bearing ores or earths, comprising a sluice and a series of riffles in said sluice, said riffles being in the form of pockets below the bottom of said sluice, and an outlet from said pockets for carrying off the concentrates settling in said pockets during the running of the sluice, and means for effecting a further separation of the gangue in said concentrates from the metal therein, said means comprising an upwardly directed spout through which the liquid carrying the lighter portions of the concentrates may flow, and a second spout through which the liquid carrying the highly concentrated metal may flow, and a screen into which said second named spout discharges, said screen having a bed of divided inert material through which the heavier metal particles may work.

3. A concentrator for metal bearing ores or earths, comprising a sluice and a series of riffles in said sluice, said riffles being in the form of pockets below the bottom of said sluice, and an outlet from said pockets for carrying off the concentrates settling in said pockets during the running of the sluice, and means for effecting a further

separation of the gangue in said concentrates from the metal therein, said means comprising an upwardly directed spout through which the liquid carrying the 5 lighter portions of the concentrates may flow, and a second spout through which the liquid carrying the highly concentrated metal may flow, and a screen into which said second named spout discharges, said screen 10 having a bed of divided inert material through which the heavier metal particles may work, and means for collecting the metal passing through said screen.

4. A concentrator for metal bearing ores 15 or earths, comprising a sluice and a series of riffles in said sluice, said riffles being in the form of pockets below the bottom of said sluice, and an outlet from said pockets for carrying off the concentrates settling in 20 said pockets during the running of the sluice, and means for effecting a further separation of the gangue in said concentrates from the metal therein, said means comprising an upwardly directed spout 25 through which the liquid carrying the lighter portions of the concentrates may flow, and a second spout through which the liquid carrying the highly concentrated metal may flow, and a screen into which said second named spout discharges, said screen 30 having a bed of divided inert material through which the heavier metal particles may work, and means for collecting the metal passing through said screen, said latter means comprising a trough and pipes leading off from the bottom of said trough.

5. A concentrator for metal bearing ores 35 or earths comprising a trough, a sluice arranged within said trough adjacent the top thereof and provided with a series of riffles, a gutter arranged adjacent the side of said 40 trough and provided with a series of riffles, an outlet pipe connected with said outlet pipe and discharging on said screen.

sluice, a screen arranged adjacent the bottom of said trough, an outlet pipe connected with said riffles, an upwardly directed spout connected with said outlet pipe and discharging into said gutter, and a downwardly directed spout connected with said outlet pipe and discharging on said screen. 45

6. A concentrator for metal bearing ores 50 or earths comprising a trough, a sluice arranged within said trough adjacent the top thereof and provided with a series of riffles, a gutter arranged adjacent the side of said sluice, a screen arranged adjacent the bottom of said trough, an outlet pipe connected with said riffles, an upwardly directed spout connected with said outlet pipe and discharging into said gutter, a downwardly directed spout connected with said outlet pipe and discharging on said screen and a 55 finely divided bed of inert material arranged upon the body of said screen.

7. A concentrator for metal bearing ores 60 or earths comprising a trough, a sluice arranged within said trough adjacent the top 65 thereof and provided with a series of riffles, a gutter arranged adjacent the side of said sluice, a screen arranged adjacent the bottom of said trough, an outlet pipe connected with said riffles, an upwardly directed 70 spout connected with said outlet pipe and discharging into said gutter, a downwardly directed spout connected with said outlet pipe and discharging on said screen, a finely divided bed of inert material arranged upon 75 the body of said screen, outlet pipes connected with said trough beneath said screen and a collector pipe connected with said outlet pipes.

In testimony whereof I hereunto affix my 80 signature.

DAVID H. DONEGAN.
